United States Patent Office.

WILLIAM BROWN, OF WEST CAMBRIDGE, MASSACHUSETTS.

Letters Patent No. 74,661, dated February 18, 1868; antedated February 6, 1868.

IMPROVED CURTAIN-FIXTURE.

The Schedule referred to in these Letters Patent and making part of the same.

TO ALL WHOM IT MAY CONCERN:

Be it known that I, WILLIAM BROWN, of West Cambridge, in the county of Middlesex, and State of Massachusetts, have invented a new and useful Improvement in Window-Shade Roller and Fixtures; and I do hereby declare that the following is a full, clear, and exact description thereof, which will enable those skilled in the art to make and use the same, reference being had to the accompanying drawings, forming part of this specification, in which—

Figure 1 is a front view of my improved window-shade roller and fixtures.

Figure 2 is a vertical sectional view taken in the line x x , fig. 1.

Figure 3 is a sectional view of the roller and bracket at one side detached.

Similar letters of reference indicate corresponding parts.

This invention relates to new and useful improvements in the construction and arrangement of window-shade rollers and fixtures, and consists in a split roller, made of two semicircular pieces lengthwise, and having on one piece a groove, and on the other a tongue fitting in the groove running down the centre of the roller, which split roller is enclosed in a split or grooved shell or barrel, surmounted with a cornice more or less ornamental. The end of the window-shade is secured in the split roller by the tongue and groove, and is wound up within the outer shell for protection from dust and light when desired. The ends of the split roller are fitted or screwed into one side of round disks or nuts, which have axes on the other side that hang in the side supporting-brackets, and in one of the brackets is a spiral spring, that bears against the axis of the roller, and thus keeps it in place at any desired height of the shade. One of the round disks or nuts on the end of the roller serves also as a cord-pulley.

This arrangement of shade-fixtures is simple and convenient, and supplies the desideratum of an ornamental piece of furniture and decoration for a window, suitable for the parlors of persons of taste with moderate means.

A represents a shade, suspended to a window-fixture, in which a is the roller, B B' the brackets, and c the upper cord-pulley. The lower cord-pulley fastening C is secured to the window-frame a little below the middle of the shade. The roller a is split down the middle from end to end. In one part a groove runs down the middle, and in the other part a corresponding tongue. The upper edge of the shade is inserted between the two parts of the split roller, and is held fast in it by the tongue and groove. The upper cord-pulley c is fitted on one end of the roller a , to clamp the two parts together, or it may be screwed thereon, and the pulley has an axis or journal on one side to hang in the bracket B . On the other end of the roller is fitted or screwed a disk, c' , which, like the cord-pulley c , is provided also with an axis or journal, hung in the other bracket B' . A spiral spring, e , is placed in the bracket to bear against the end of the journal and keep the roller steady. A shell or barrel, D , which may be made in one or more pieces or sections, is placed around the split roller a . The shell D is slotted from end to end in one side, for the passage of the shade through it when placed over the roller, as shown in fig. 2. A cornice or ornamental centre-piece, E , is fitted upon the middle of the shell D , and keeps it in place over the split roller a . These parts may be made of wood or any suitable material.

Having thus described my invention, what I claim as new, and desire to secure by Letters Patent, is—

1. The split roller a , with or without a tongue and groove, for securing the upper end of the shade, substantially as described, in combination with the case or shell D , as and for the purpose specified.
2. The combination of the split roller a , the nuts or disks c c' , and the brackets B B' , arranged and operating substantially as described.
3. The combination of the split roller a , the shell D , and the cornice E , constructed, arranged, and operating substantially as described.

WM. BROWN.
